UNITED STATES PATENT OFFICE.

KAREL VONDRA, OF KYSPERK NAD ORLICI, CZECHOSLOVAKIA.

TYPEWRITER.

Application filed November 17, 1924 Serial No. 750,379.

To all whom it may concern:

Be it known that I, KAREL VONDRA, a citizen of the Czechoslovakian Republic, residing at Kysperk nad Orlici, Czechoslovakia, have invented certain new and useful Improvements in Typewriters, of which the following is a specification.

This invention relates to typewriters and consists in combining, as hereinafter set forth and claimed, a plurality of type control levers and key levers with coupling elements arranged so that each type control lever requires the depression of two keys for its operation and so that a depression of any two key levers together causes the operation of a definite type control lever.

This arrangement has the advantage that a large number of types can be controlled by means of a comparatively small number of keys.

Fig. 1 of the accompanying drawings represents a diagram showing one mode of coupling the key levers and type control levers,

Fig. 2 is a plan of the mechanism, and Fig. 3, a side view of the same.

Fig. 4 is a view of a thrust member whereby the movement of a pair of key levers is transmitted to the type control lever.

Fig. 5 is a front view showing a modification of the mechanism, and

Fig. 6, a side view of this arrangement.

Fig. 7 is a front view of a still further modification,

Fig. 8, a plan, and

Fig. 9, a side view of the same.

Figs. 10 and 11 represent each a front view and a plan of alternative thrust members, and

Fig. 12 is a diagram showing the coupling of the key levers in the construction according to Figs. 7 to 9.

The type control levers 5 and the key levers 1 are arranged to rock about a universal shaft 4. In the construction according to Figs. 1 to 4 each type control lever 5 is provided at its free end 3 with a thrust member in the form of a transversely arranged pivoted beam 2 having arms of equal length. The beam 2 co-operates with two key levers for the engagement with which it has at the end of each arm an upright 6. A depression of one of these key levers merely rocks the beam 2 about its pivot 3 without affecting the type control lever. If both

ends of the beam are engaged, however, by the depression of both key levers, the beam opposes the movement and causes its type control lever to be operated. The beams 2 are of different lengths and span two or more key levers, and each key lever co-operates with several beams, the arrangement being such that a depression of any two key levers causes a definite type control lever to be operated.

Fig. 1, in which the type control levers are indicated by the circles 3, shows the arrangement for ten key levers whereby, when depressed in pairs as just described, forty-five type control levers may be operated. By the addition of another lever, the number of type control levers available would be fifty-five.

As an alternative to the beam 2, the type control levers 5 may be provided with brackets 14 in which a rod 15 is adapted to slide, as shown in Fig. 5. The ends of the rods are bevelled for co-operation with bevelled lugs 16 carried by the key levers 1. A depression of only one key lever causes a lateral displacement of the rod 15. When both key levers are depressed together, the rod cannot shift, and the depression will therefore be transmitted to the type control lever.

In the modified arrangement shown in Figs. 7 to 12, the thrust members are composed of short pellets 15' which are fitted transversely in the type control levers 5 so as to be capable of lateral displacement, the ends of the pellets being rounded off for engagement with the bevelled edges 11 of the key levers 1. In this instance there is a key lever at each side of each type control lever, and both key levers must be depressed in order to operate the type control lever, one key lever being common for both type control levers adjacent to it. To enable a large number of type control levers to be operated by means of a small number of keys actuated in pairs, according to the invention, the key levers are connected by means of bridge pieces 7 into intermeshing groups, and each group is controlled by means of a key. Each group has one lever, and no more, adjacent to a lever of each of the other groups, so that any two groups acted upon cause the operation of a definite type control lever. Fig. 12, from which the key levers themselves are absent, shows the grouping of the

levers for forty-five type control levers, for the operation of which ten groups of key levers, and thus ten keys, are required.

Preferably, the bridge pieces 7 are connected to their levers by means of tail pieces 8 and rivets 9. For convenience of illustration, the bridge pieces 7 are shown in Figs. 8 and 9 to be supported by straight uprights, but the latter must in practice, if placed close together, be curved about the shaft 4, as shown by dotted lines in Fig. 9, in order to clear each other.

The slideable pellets 15' may be replaced by pendants 2' (Fig. 10) having bevelled heads 12 for engagement with the key levers. When only one lever is depressed, the pendant swings about the pivot 3. When both key levers are depressed, the head of the pendant opposes the movement and causes the type control lever to be operated. Another alternative is shown in Fig. 11 where the thrust member is composed of a swivelled plate 2'' having two wings which must both be acted upon in order to operate the type control lever.

The arrangement of Figs. 7 to 9 has the advantage that the weight of the rocking masses can be concentrated near the shaft 4, a noiseless operation being thus ensured.

The type control levers 5, instead of carrying the types themselves, may be adapted to operate a type wheel in known manner. The usual shift keys may be employed to double or treble the number of characters controlled by each bar.

The relative position of the different ele-

ments can be varied according to requirements.

I claim:

1. In a typewriter, a shaft, a plurality of type control levers arranged on said shaft, key levers arranged on said shaft alternately with the type control levers, a thrust member connected to each type control lever so as to cooperate with adjacent key-levers for operating the type control lever, each thrust member being arranged so as to require the depression of both key levers adjacent to it for operating its type control lever, bridge pieces connecting the key levers into intermeshing groups so that any type control lever can be operated by a depression of a definite group of key levers, and an actuating key for each group of key levers.

2. In a typewriter, a shaft, a plurality of key levers arranged on said shaft, a type control lever arranged on said shaft between each pair of adjacent key levers, a thrust member carried by each type control lever so as to be engaged by the key levers when the latter are depressed, the thrust members being adapted to yield laterally at the depression of only one key lever and to oppose the depression of both adjacent key levers so as to operate its type control lever, bridge pieces connecting the key levers into intermeshing groups so that each group has a lever adjacent to a lever of each of the other groups, and an actuating key for each group of key levers.

KAREL VONDRA.
